G. F. VOIGHT,
SIGNALING HORN.
APPLICATION FILED JULY 3, 1916.

1,235,743.

Patented Aug. 7, 1917.

UNITED STATES PATENT OFFICE.

GEORGE F. VOIGHT, OF SAN FRANCISCO, CALIFORNIA.

SIGNALING-HORN.

1,235,742

Specification of Letters Patent.

Patented Aug. 7, 1917.

Application filed July 8, 1916. Serial No. 107,333.

To all whom it may concern:

Be it known that I, GEORGE F. VOIGHT, a citizen of the United States, residing at San Francisco, in the county of San Francisco and State of California, have invented a new and useful Signaling-Horn, of which the following is a specification.

My invention relates to improvements in signaling horns, such as are employed on 10 automobiles or similar vehicles, to give a warning of the approach of the vehicle, and while I have designed it especially for this use, it is obviously adapted for other uses.

One of the objects of my invention being 15 to provide a horn that can, at the option of the operator, be operated either by hand or by electrical means, or by both of said means at the same time. Other objects of my invention will appear as the description proceeds, it being understood that changes in the precise embodiment of the invention herein disclosed can be made within the scope of what is claimed without departing from the spirit of the invention.

25 In the accompanying drawings illustrating the invention.—

Figure 1 is a side sectional view of the horn, certain portions being broken away, and other portions being shown in elevation.

30 Fig. 2 is a top sectional view of the horn on line A A, in Fig. 1.

Fig. 3 is a rear-end sectional view of the horn on line B B, Fig. 1.

Fig. 4 is a side sectional view of a portion 35 of the horn in a modified form, on a line relative to the horn, indicated by line C C, Fig. 6.

Fig. 5 is a sectional end view of the central plunger member forming a portion of 40 the horn, in the said modified form.

Fig. 6 is a top plan view of one of the parts forming a portion of the horn in the said modified form, and is drawn on a scale smaller than the aforesaid figures.

45 Similar numerals refer to similar parts throughout the several figures.

The numeral 1 designates a frame piece, having a central opening 2 in which is disposed the forward portion of a diaphragm assembly hereinafter fully described, tongues 3, 3 forward struck and to which is secured by suitable means the said forward portion of the said diaphragm assembly, a suitable mounting portion 4 which may be 55 extended outwardly at right angles to the

flat side of the lower portion of the frame piece 1, or it may be a direct downward continuation of it, suitable holes 5 for the terminals 6 and 6^a and suitable screw-bolt holes 7. To the front flat side of the frame piece 1 is suitably fitted a suitable resonator 8, and to the rear flat side thereof are fitted cover pieces 9, 10 and 11 by suitable screw-bolts 12, 12^a and 13; the screw-bolts 12 and 12^a also performing other functions. 60 The said diaphragm assembly, hereinbefore mentioned, consists of two flexible, vibratable, diaphragms 14 and 14^a, which may be made of any suitable material, disposed flat side to flat side, spaced a suitable distance 70 from each other and approximately parallel with each other, a plunger 15 centrally disposed between said two diaphragms, actuating springs 16 and 16^a, one or more of said springs being disposed on both the upper and lower sides of the said plunger 15 and between it and the said diaphragms 14 and 14^a, a suitable spacing ring 17, stiffening rings 18 and 18^a, insulating rings 19 and 19^a and an electromagnet assembly consisting 75 of a core 20, winding 27, yoke 21, contact spring 22, armature 23, armature fingers 24, armature spring 25, contact spring adjusting screw 26 and suitable circuit means.

The forward portion of the said diaphragm assembly is secured, as hereinbefore mentioned, to the tongues 3, 3, and the rearward portion is secured by the cover pieces 9, 10 and 11. The cover piece 9 being in the form of a band passing around the 80 back and sides of the said diaphragm assembly, with its ends extending to the rear side of the frame piece 1 and terminating in lips 32, 32, by which means it is suitably fastened to said frame piece. The said cover piece 9 having a rear end aperture for the passage of the plunger 15. The cover piece 10 consists of a flattened member having a straight transverse front edge terminating in a lip 32^a which is turned upwardly and disposed against the rear side of the frame piece 1 and adjacent its upper edge, and an off-set 33 struck downward forming a lip 34 which is disposed against the top rearward portion of the diaphragm assembly 90 and suitably fastened thereto. The cover piece 11 is open at the top and front sides, has a circular rear side, the upper portion of which is attached by means of a lip 35 struck outwardly and extending along 100 105 110

around said open sides or edges, to the rear lower portion of the said diaphragm assembly, extending thence forwardly to and against the frame piece 1, to which it is attached by means of the said lip 35. The functions of the said cover pieces are to form a protective covering for, and a chamber inside of which is disposed and to the inner sides of which is attached for support, 5 the said diaphragm assembly, and it is obvious that if preferred, the same may be made in one piece, or two pieces or any suitable number of pieces; nor need it be shaped strictly on lines illustrated and described. 10 Interposed between the upper diaphragm 14 and the lower diaphragm 14^a is the spacing ring 17, which may be made of metal or other suitable material, has through its front and rear walls suitable guide holes 36 in 15 which is slidably disposed the plunger 15, and suitable openings 37 through its side walls for egress of the sound waves produced by the vibration of the diaphragms. In Figs. 2 and 3 I show the said opening 37 in 20 elongated circular holes, while in Figs. 1 and 4 I have shown the openings more in the form of a slot cut through the ring 17 and extending from near one portion of the plunger 15 around to near a second portion 25 of the said plunger.

The plunger 15 has an outer end extending a suitable distance rearwardly from the said diaphragm assembly and terminates in a suitable hand piece 38, and an inner end 30 extending a suitable distance inwardly through the said diaphragm assembly and into the opening of the resonator 8, and has a suitable hole 39 transversely through the end thereof, into which hole is fitted one 35 end of a suitable coil spring 40, the other end of said spring being suitably attached to a bracket or fastening 41 fitted to one of the tongues 3 by means of a screw 42.

The spring 40 is in normal position when 40 it is closed and its coils or scrolls lie close upon each other, and when in such position the plunger 15 will be extended outwardly in the direction of the hand piece 38, as far as it will go.

As the plunger 15 is pressed inwardly or 45 forwardly along through the guide holes 36, the coil spring 40 will be forced to open out longitudinally and against its tension, and when said inward pressure on the plunger 15 is released, the said tension of 50 the said spring will cause it to contract and close up longitudinally, whereby the said plunger is forced outwardly and rearwardly again and in position in which it is ready 55 to receive the next thrust of the operator's hand.

On the upper and lower sides or the sides next to the flat inner sides of the diaphragms 14 and 14^a, of the intermediate portion of 60 the plunger 15 are suitable bevel teeth 43

extending cross-wise to the shank of the plunger, which teeth engage in regular order, when the said plunger is moved inwardly or outwardly, the bevel wedge-pieces 44 of the actuating springs 16 and 16^a, thereby 70 forcing the said actuating spring outwardly and away from the plunger 15, causing the hammers 45 to engage, by striking or pressing, the diaphragms 14 and 14^a, either directly or by means of the wear pieces 31 centrally disposed thereon, thereby 75 causing the said diaphragms to be deflected and vibrated. The actuating springs 16, 16^a may be made up of a plurality of individual members as shown in Figs. 1, 2 and 3, and 80 wherein I show a horn having two of said springs disposed above and two below, the plunger 1, while in the modified form illustrated by the Figs. 4 and 6, I make both the upper and the lower sets of these springs out of one piece of metal, leaving the outer ends 85 of the said springs integral with the margin of the disk from which they were cut. In the latter form I employ four spring members on the upper, and four on the lower, 90 side of the plunger 15; however, any convenient and suitable number of said springs or spring members may be employed. The wedge-pieces 44 may be disposed upon the actuating springs 16, 16^a, in positions at random relative to the bevel teeth 43, however, 95 I prefer to so place them that they will move in regular and prearranged order, and so that each of the hammer pieces 45 will in regular order and one after the other at 100 regular intervals, engage the diaphragms 14 and 14^a. In the regular form I show the wedge-pieces 44 attached to the actuating springs 16 and 16^a, a short distance outwardly from the inner ends of said springs, 105 while in the modified form of the horn the wedge-pieces are disposed substantially at the inner ends of the said springs and integral with the hammer pieces 45.

The outer ends of the actuating springs 110 16 and 16^a, in both the regular and the modified forms of the horn, are seated directly upon the flat sides of the spacing ring 17. And in the regular form the diaphragms 115 14 and 14^a are seated directly against the flat outer ends of the said actuating springs, while in the modified form I employ intermediate upper and lower spacing rings 17^a and 17^b. The said springs may, however, if so preferred, be attached directly to the flat 120 sides of the diaphragms any suitable place inside of the margins of the said diaphragms. Upon the margins of the outer flat sides of the diaphragms 14 and 14^a I place a stiffening ring 18 and 18^a, and disposed against 125 the lower side of the stiffening ring 18^a, are insulating rings 19 and 19^a, and interposed between said latter rings is an armature spring 25 and a contact spring 22, and against the lower side of the ring 19^a is 130

fitted the yoke 21 of the said electromagnet assembly; the whole being securely fastened together by means of the screw-bolts 12 and 12^a disposed in and through suitable holes 5 in the outer ends and margins of the said described members and parts forming the said diaphragm assembly, the said screw-bolts performing also functions hereinbefore mentioned.

10 It is intended that the diaphragm 14^a may be agitated either by means of the hand operated plunger 15 or by means of the electromagnet element or assembly just above described; however I do not claim 15 any part of the said electromagnet assembly as my invention, and any other suitable electromagnet element may be employed.

10 In the particular form of electromagnet element illustrated, the path of the electric current will be, presuming to begin at the terminal 6, over the end of the coil wire attached to said terminal, thence through the coil 27, thence over the other end of the coil wire to the contact spring 22, thence to 25 the armature 23, thence to the armature spring 25, thence to the knee-piece 28, thence over the wire 29 to the terminal 6^a and to the battery or generator. In the means just described, it is understood that the contact 30 spring 22 must be properly insulated. The magnetic flux path being formed by the core 27, yoke 21 and armature 23. It will be seen therefore, that when the horn is operated electrically, the core 27 will become charged 35 magnetically and attract the armature 23, which will cause the fingers 24 to engage the expanded head 30 which is connected with, or integral with, the wear-piece 31 attached, centrally, to the diaphragm 14^a, thereby deflecting and vibrating the said diaphragm, the said armature at the same time separating it from contact with the contact 40 spring 22 and thereby breaking the circuit, when the tension of the said armature spring 25 will force the armature 23 to return to normal position which is a pre-arranged distance from the core 20, and in engagement again with the contact spring 22. When it is desired to operate the horn 45 by hand operated means, the plunger 15 is pushed or pressed forwardly into the horn and against the tension of the coil spring 40, which will engage the bevel teeth 43 with the wedge-pieces 44 attached to the actuating 50 springs 16, 16^a, pressing or striking the said springs by means of the hammer pieces 45, against the diaphragms 14 and 14^a, deflecting and vibrating said diaphragms.

When the said pressure upon the plunger 60 15 is released, the tension of the then longitudinally expanded coil spring 40 will force the said plunger outwardly and rearwardly again in the direction of the hand piece 38, as far as it will go, thereby engaging again 65 the bevel teeth 43 with the wedge-pieces 44

and repeating the action of the springs 16, 16^a, and the hammer pieces 45, upon the diaphragms 14 and 14^a.

It is the case sometimes, in a horn containing a single means of operation, that is 70 a horn that can be operated by hand means only, or a horn that can only be operated by electrical means, that the said means becomes inoperative, and the horn useless as to its warning power. While a horn having 75 two separate means of operation, when one of said means becomes inoperative from any cause whatsoever, then the other means may be used with which to give warning. The horn may also be so constructed that one of 80 the said means will produce a louder warning than the other, in which case the said louder means can be employed when it is desired to give a loud warning, and the other means employed when it is desired to give 85 a milder warning. The two means could also be used jointly and at the same time, if desired.

Having thus described my invention, what I claim is:

1. In a device of the kind described, the combination of a non-flexible resonator, a casing or covering, a vibratile diaphragm adapted when vibrated to sound warning signals, means for vibrating said diaphragm 90 from one flat side thereof by electromagnetic attraction, and means whereby said diaphragm can be vibrated from the opposite flat side thereof by manual operable mechanism, either of said means being operable independently of the other, said manual operable mechanism including an operating member extending out through the walls of said casing or covering and adapted for engagement with the hand of the operator. 100

2. In a device of the kind described, the combination of a hollow non-flexible resonator, a casing or covering, means for securing said resonator and said casing or covering together so as to form an inclosed chamber opening out through said hollow resonator, a vibratile diaphragm disposed inside said chamber, said diaphragm being adapted when vibrated to set up and emit 110 sound waves adapted as signals, said sound waves having egress through said hollow resonator, means whereby said diaphragm can be vibrated from one flat side thereof by electromagnetic attraction, and means whereby said diaphragm can also be vibrated from the opposite flat side thereof by manually operable mechanism, said manually operable mechanism including an operating member projecting out through 120 the walls of said chamber and adapted for engagement with the hand of the operator.

3. In a device of the kind described, the combination of a hollow non-flexible resonator, a casing or covering, means for secur- 130

ing said resonator and said casing or covering together so as to form an inclosed chamber having an exit through said resonator, a vibratile diaphragm disposed inside 5 said chamber, said diaphragm being adapted when vibrated to produce sound waves intended as sound signals, said sound waves having egress from said chamber through said exit; electromagnetic means adapted 10 when actuated to vibrate said diaphragm from one flat side thereof, and means whereby said diaphragm also can be vibrated from the opposite flat side thereof by manual energy independent of said electromagnetic means, said manual energy means including means projecting through the walls of said chamber adapted to be engaged by the hand of the operator, said resonator being adapted for amplifying said sound 15 waves produced by said diaphragm when vibrated.

4. In a device of the kind described, the combination of a resonator, a casing or covering, a diaphragm adapted when vibrated 20 to sound signals, electromagnetic means adapted for vibrating said diaphragm from one flat side thereof, and manual operable means adapted to vibrate said diaphragm from the opposite flat side thereof by impinging said opposite flat side.

5. In a device of the kind described, the combination of a resonator, a casing or covering, a vibratile diaphragm adapted when vibrated to sound signals, electromagnetic 25 means adapted when actuated to vibrate said diaphragm from one flat side thereof, and manually operable means adapted to vibrate said diaphragm from the opposite flat side thereof by tapping against said opposite side adjacent its center, said last mentioned means being operable independently of said first mentioned means and includes a member extending through the walls of 30 said casing or covering adapted to be engaged by the operator's hand when operating said manually operable means.

6. In a device of the kind described, including a vibratile diaphragm, means whereby said diaphragm can be vibrated either 35 electromagnetically or by hand-operated means, said hand-operable means including a plurality of flexible springs, and means whereby said springs can be impinged upon one flat side of said diaphragm thereby 40 vibrating it.

7. In a device of the kind described, including a hollow resonator, a casing or covering, a vibratable diaphragm adapted when vibrated to produce sound signals, said 45 sound signals passing out through the longitudinal opening through said resonator, the combination with means whereby said diaphragm can be vibrated from one flat side thereof by electromagnetic attraction, and 50 means whereby said diaphragm also can be

vibrated from the opposite side thereof by hand-operated means independent of said first mentioned means, of a flat-frame piece having a comparatively large central opening therethrough disposed between said resonator and said casing or covering, said frame-piece having a mounting portion whereby said device or horn can be rigidly and securely fastened to a suitable part of a vehicle or the like.

8. In a device of the kind described, the combination with a hollow resonator, a casing or covering, means for securing said resonator and said casing or covering together forming thereby an inclosed chamber 70 having an exit through said hollow resonator, a vibratile diaphragm adapted to produce sound signals when vibrated disposed inside said chamber, said sound signals having egress through said exit, and means disposed also inside said chamber whereby said diaphragm can be influenced from one flat side thereof by electromagnetic means and vibrated, of means whereby said diaphragm when not under said influence can be vibrated from the opposite side thereof by hand operated means, said hand operable means being also disposed inside said chamber with an operating member adapted to be engaged by the operator's hand projecting a 80 suitable distance out through the walls of 85 said chamber.

9. In a horn of the character described, the combination of a hollow resonator, a casing or covering, means for securing the resonator 100 and the casing or covering together forming thereby an inclosed chamber having an exit through said hollow resonator, a vibratile diaphragm disposed inside said chamber, the diaphragm being provided with a central 105 wear piece, electro-magnetic means also disposed inside the chamber whereby the diaphragm can be vibrated by electro-magnetic attraction, and manually operable means secured inside said chamber and movable relative to the walls thereof whereby the diaphragm can also be vibrated by mechanically engaging and disengaging alternately said wear piece, said manually operable means including a movable operating member extending 110 out through the walls of the chamber.

10. In a horn of the character described, the combination of a resonator, a casing or covering, and a diaphragm, the diaphragm having a central wear piece and being vibratable both by electrically controlled means and by manually operable means, the last mentioned means being adapted to vibrate the diaphragm by engaging and disengaging alternately the said wear piece and 115 is provided with a movable operating member extending out through the walls of the chamber.

11. In a horn of the character described, the combination of a resonator, a casing or 120

- covering, and a vibratile diaphragm adapted when vibrated to sound warning signals, the diaphragm having a central wear piece and being vibratable both by electrically operable means and by mechanically operable means, the mechanically operable means being adapted to vibrate said diaphragm by impinging said wear piece, either of said means being operable independently of the other.
12. In a horn of the character described, a hollow resonator, a casing or covering, means for securing the casing or covering together forming thereby an inclosed chamber having an exit through the resonator, a vibratile diaphragm disposed inside the chamber, electro-magnetic means disposed inside the chamber whereby the diaphragm can be vibrated by electro-magnetic attraction, and manually operable means for vibrating the diaphragm independently of said electro-magnetic means, the manually operable means including a driven member, or driven members, supported by the horn independently of the diaphragm and engageable with the diaphragm for vibrating it and a driving member for driving the driven member, or driven members, the driving member having a portion projecting out through the walls of the chamber adapted to be engaged by the operator's hand.
13. In a horn of the character described, a hollow resonator, a casing or covering, means for securing the casing or covering and the resonator together forming thereby an inclosed chamber having an exit through the resonator, a vibratile diaphragm disposed inside the chamber, electro-magnetic means disposed inside the chamber whereby the diaphragm can be vibrated by electro-magnetic attraction, and manually operable means, the manually operable means including driven means supported by the horn independently of the diaphragm and engageable with the latter for vibrating it and driving means for driving the driven means, the driving means having a portion projecting out through the walls of the chamber adapted to be engaged by the operator's hand.
14. In a horn of the character described, a hollow resonator, a casing or covering, means for rigidly securing the casing or covering and the resonator together forming thereby an inclosed chamber having an exit through the hollow resonator, a vibratile diaphragm disposed inside the chamber, electro-magnetic means supported by the horn whereby the diaphragm can be vibrated by electro-magnetic attraction, and means supported also by the horn and operable independently of said electro-magnetic means whereby the diaphragm can be vibrated by manually controlled mechanism, the manually controlled mechanism embodying driven means supported by the horn independently of the dia-
- phragm and engageable with the latter for vibrating it and driving means for driving the driven means.
15. In a horn of the character described, the combination of a hollow resonator, a casing or covering, means for securing the resonator and the casing or covering together forming thereby an inclosed chamber having an exit through said resonator, a vibratile diaphragm disposed inside the chamber, means supported by the horn whereby the diaphragm can be vibrated by electro-magnetic attraction, and means supported by the horn and movable relative thereto whereby the diaphragm can also be vibrated by manually operable mechanism, the manually operable mechanism being adapted to vibrate the diaphragm by alternately engaging and disengaging centrally one flat side thereof and, includes a hand engaging element extending out through the walls of the chamber adapted to be engaged by the operator's hand.
16. In a horn of the character described, the combination of a resonator, a casing or covering, a vibratile diaphragm adapted when vibrated to sound warning signals, the diaphragm being provided with a central non-flexible wear-piece, electrically influenceable means supported by the horn whereby the diaphragm can be vibrated by electrically influencing said means, and manually operable means supported by the horn and alternately engageable and disengageable with said wear-piece for vibrating the diaphragm.
17. In a horn of the character described, a hollow resonator, a casing or covering, means for securing the resonator and the casing or covering together forming thereby an inclosed chamber having an exit through the resonator, a vibratile diaphragm adapted when vibrated to sound warning signals, the diaphragm having a non-flexible central wear-piece or anvil, electrically controlled means supported by the horn whereby the diaphragm can be vibrated by magnetically influencing the diaphragm and its wear-piece or anvil, and manually controllable means supported by the horn whereby the diaphragm can be vibrated by manually operable and manually controlled means by engaging said wear-piece or anvil with said last mentioned means.
18. In a horn of the character described, a hollow resonator, a casing or covering, means for securing the resonator and the casing or covering together, a pair of vibratile diaphragms adapted when vibrated to sound warning signals, electro-magnetic means for vibrating one of the diaphragms, and manually operable means operable for vibrating the second one of the diaphragms.
19. In a horn of the character described, a hollow resonator, a casing or covering,

means for securing the resonator and the casing or covering together, a pair of vibratile diaphragms supported by the horn, the diaphragms when vibrated being adapted to 5 sound warning signals, electro-magnetic means supported by the horn and adapted for vibrating one of said diaphragms, and manually operable means supported by the horn and operable for vibrating the second 10 one of said diaphragms.

20. In a horn of the character described, a hollow resonator, a casing or covering, means for securing the resonator and the casing or covering together forming thereby 15 an inclosed chamber having an exit through the hollow resonator, a pair of vibratile diaphragms disposed inside the chamber, the diaphragms adapted when vibrated to sound warning signals, electrically controlled means 20 for vibrating one of the diaphragms, and mechanically controlled means whereby the second one of said diaphragms can be vibrated.

21. In a horn of the character described,

a hollow resonator, a casing or covering, 25 means for securing the resonator and the casing or covering together forming thereby an inclosed chamber having an exit through the hollow resonator, a plurality of vibratile diaphragms disposed inside the chamber, 30 the diaphragms adapted when vibrated to sound warning signals, electrically controlled means for vibrating one division of said diaphragms, and mechanically controlled means whereby the remaining division of 35 said diaphragms can be vibrated.

22. In a horn of the character described, a hollow resonator, a casing or covering, means for securing the resonator and the casing or covering together forming thereby 40 an inclosed chamber having an exit through said hollow resonator, a vibratile diaphragm disposed inside the chamber and adapted to be vibrated by electro-magnetic attraction, and a second vibratile diaphragm disposed 45 also inside said chamber and adapted to be vibrated by manually operable means.

GEORGE F. VOIGHT.
